UNITED STATES PATENT OFFICE.

AUGUST L. SEGELHORST, OF WHITTIER, CALIFORNIA.

PACKING DEVICE.

Application filed October 11, 1922. Serial No. 593,855.

My invention relates to packing devices such as are employed in pumps, engines, and devices in which fluids are handled under pressure.

5 My invention is intended primarily for use with oil well pumping equipment, but is adapted to a wide range of uses, as will be made evident in the following specification. The present form of packing box employed 10 with pumps and engines, provides a chamber surrounding the reciprocating piston rod, or pump rod, in which packing material is compressed by a gland which is forced against the packing by means of a screw cap, 15 bolts, or resilient means. When it becomes necessary to renew or make addition to the packing contained in these packing boxes it is necessary to shut down the apparatus, and in the case of engines or compressors, to re- 20 move the pressure from the cylinder whereupon the gland is taken out and additional or new packing placed within the chamber.

Oil wells from which oil is being pumped are often subjected to pressure heads due to 25 the accumulation of gas pressure within the well. Such pressure heads occurring at a time when the packing box is open for the purpose of renewing the packing result in oil being forced up through the packing box 30 and distributed over the derrick platform and pumping equipment. In the ordinary type of packing box, packing is employed in the form of rings or in continuous lengths which are coiled within the packing box and 35 then forced down into a compact form by the gland. Such packing when worn is discarded as being of no further value.

It is an object of my invention to provide 40 a packing device to which the addition of packing may be made without the necessity of shutting down the equipment, and without the necessity of opening the packing box.

It is a further object to provide a packing 45 device in which packing is employed in comminuted form, and in which this comminuted packing is entirely used up, the compensation for wearing away thereof being made by the addition of new packing.

It is a further object of the invention to 50 provide a device of this character in which the packing is fed, in comminuted form, into the packing chamber by means of a spiral screw, or equivalent feeding mechanism.

An important advantage of my invention 55 is that it may be kept in operating condition without interfering with the operation of the

equipment with which it is employed, and that to it new packing may be added at intervals to make up for the reduction due to wear, also without shutting down the 60 equipment or the necessity of opening the packing box as is necessary when it is desired to repack those packing boxes now commonly employed.

The especial advantages of my invention 65 and further objects thereof will be made evident hereinafter.

Referring to the drawings which are for illustrative purposes only:

Fig. 1 is a partially sectioned view showing 70 my invention employed as a means for packing around the polished rod of an oil well pump.

Fig. 2 is a section taken on a plane represented by the line 2—2 of Fig. 1. 75

Fig. 3 is a sectional view showing the preferred form of my device equipped so that it will be self-centering upon a polished rod which is not in perfect alignment with the packing box. 80

Figs. 3 to 7 inclusive, are views showing various forms of my invention.

The preferred form of my invention as shown in Fig. 1 provides a standard form of packing box 11, which is attached to the top 85 12 of a string of tubing by means of a collar 14, having provided therein a packing chamber 15. This packing box 11 is threaded at its upper end 16 and has a collar member 18 screwed thereupon against a gasket 19. The 90 member 18 is adapted to receive a conoidal screw 20, and has spiral threads 22 formed therein which are sloped oppositely to the threads 23 of the screw 20. A hub 25 extends upwardly from the screw 20 and has a babbitted bore 26 through which the polished rod 27 of the pumping equipment extends and reciprocates. To the upper end 95 of the hub 25 a ring 28 is secured from which operating arms 29 extend. A bowl 31 threads upon the member 18 at 32, this bowl 100 31 being provided with circular openings 33, which furnish communication between the interior of the bowl 31 and the interior of the conical member 18. 105

As hereinbefore stated packing has been utilized in the form of rings or continuous lengths. The use of comminuted packing I believe to be entirely new and original with me, and especially the use of such packing 110 with such a device as shown in Fig. 1. A comminuted packing 35 may be of metallic,

or of rubber and fabric composition, this packing being provided in chunks of a suitable size to pass through the openings 33 as shown at 36. The comminuted packing being placed in the bowl 31 as shown, the chamber 15 having been previously filled therewith, the screw 20 is rotated in a right hand direction by use of the bars 29. The comminuted packing drops through the openings 10 33 and is engaged by the spiral threads 23 of the screw 20, and is thereupon carried downward and forced into the chamber 15.

The use of screws for feeding materials is recognized as being old, but the arrangement 15 shown in Fig. 1 provides a new and useful combination whereby a packing box may be supplied with packing material as the packing therein is worn, and further provides a means whereby unlimited compression may 20 be placed upon the packing within the packing chamber to care for the pressures which must be worked against.

This preferred form of my invention may 25 be quickly installed with any of the common types of packing boxes. The disposal of the screw thereof, concentrically upon the polished rod 27, provides a means whereby the packing material may be fed into the packing chamber in an axial direction and 30 results attained, equal to those obtained by the use of a follower. By the axial feeding in of the comminuted packing an equal distribution of pressure is provided throughout the packing chamber.

In Fig. 3 I show an oil well packing head 40 provided with flanges 41. Upon the member 40 a casting 42 may be bolted by means of studs 43. The casting 42 provides a bowl 44 and a bore 45 having a curved 40 upper face 46. A circular opening 47 extends through the web 48 which separates the bowl 44 from the bore 45, through which opening the hub 49 of the screw 50 extends. Upon a rocker plate 52 a cooperating member 53 having a curved upper surface 54 is mounted. This cooperating member 53 has a conical bore which fits over the screw 50 and is somewhat smaller in external diameter than the interior of the bore 45. For the 45 purpose of preventing the rotation of the member 53 within the bore 45, a round pointed screw 56 is threaded through the wall of the member 42, and engages a blind opening 57 in the outer face of the cooperating member 53. The member 53 may be moved laterally within the bore 45 so as to compensate for a mis-alignment of the polished rod 58, the opening 47 through the web 48 being also of greater diameter than the hub 49. Circular openings 581 are provided in the web 48 through which the comminuted packing 59 placed in the bowl 44, may pass into the spaces between the threads of the screw 50, so that it may be fed as 60 desired into the packing chamber 60 pro-

vided by the packing head 40. In this form of my device I show a capstan ring 61, engageable by a lever 62, by which the screw 50 may be rotated upon the polished rod 58 to accomplish the desired feeding of the comminuted packing. 70

In various types of compressors and in steam engines it is necessary to employ stuffing boxes upon the piston rods in order to prevent the leakage of fluids from the cylinders. In Fig. 4 I show my invention adapted to such use, in which figure are illustrated a casting 65 having a plate 66 which may serve as the cylinder head of the device upon which it is being used, and a packing chamber 67 having a cap 68 threaded upon the end thereof. Extending perpendicularly from the chamber 67 is a tubular shaft 69 in which a feed screw 70, adapted to be rotated by a handle 71, operates. The comminuted material is supplied in a bowl 73 having a cover 74 and a spring actuated plunger 75 which bears against the packing 77 and forces it into the tubular shaft 69 so that it may be fed into the packing chamber 67 as the feed screw 70 is rotated by turning the handle 71. Babbitt, or bearing metal, end plates 79 are provided in the ends of the packing chamber for centralizing the piston rod 80 within the packing device. My invention is of particular utility in the use shown in Fig. 4, as it provides a means for keeping the packing absolutely tight, without the necessity of opening the packing chamber for the purpose of 100 adding new packing material. This has a decided value in devices which are employed for handling acids, as the packing boxes used with such equipment must be repacked, which is comparatively often owing to the deteriorating action of the acids upon the packing material. It will be perceived that my invention provides a means for continuously supplying the packing material to such a chamber, thus replacing the deteriorated packing and keeping the packing box absolutely 105 tight. 110

Under certain conditions it is advisable to provide a continuous automatic feeding of packing material into a packing chamber. In Figs. 5 and 6 I show my invention adapted to this use. Upon a packing head 85 a cap 86 is shown threaded at 87 and has attached thereto a member 88 in which a feed screw 89 operates. This feed screw is supplied with the comminuted packing 90 from a receptacle 92 provided in the cover 93. The screw 89 is held in the member 88 by a screw plug 94 through which the shaft 95 of the screw extends outward beyond the face of the plug 94. Loosely mounted upon the shaft is a vertical arm 96 upon which a 115 120 125 130

pawl 97 is mounted by means of a screw 98, and rigidly secured to the end of the shaft 95 is a ratchet wheel 99 which is held upon the shaft by a nut 100. The upper 5 end of the arm 96 is provided with a fork 103 which engages the polished rod 104 so that the deflection of the polished rod as it reciprocates will cause a slight backward and forward reciprocation of the arm 96 as indicated by the dotted lines 105 in Fig. 6. Thus, it will be perceived that as the polished rod 104 is reciprocated, the arm 96 will be provided with a slight reciprocating 10 rotary action which will cause the pawl 97 to consecutively engage the teeth of the ratchet 99, and thereupon rotate the screw 89, which in turn continuously feeds the 15 comminuted packing into the packing chamber 107.

20 In the device shown in Fig. 5 I also employ Babbitt guide plates 108 and 109 for centralizing the polished rod 104 through the packing chamber and for receiving the wear of the polished rod as it passes through 25 the cap 86. The friction plate 109 may be held in position in the top of the cap 86 by a small screw 110. A small cup 112 is threaded upon the top of the cap 86 into 30 which any oil that may be forced through the packing member may collect, and a drip spout, in the form of a pipe 113, is provided whereby the oil may drain from the cup 112 into a suitable receptacle, not shown.

In the horizontal sectional view shown in 35 Fig. 7 I show the manner in which a feed screw 150 may be adapted to feed a continuous strip of packing material 160 tangentially into a packing chamber 151 provided by a casting 152. It is advantageous 40 to feed the strip of material into a packing chamber in this manner, as the direct pressure of the entering of the material is not then exerted directly against the shaft 153 but is added to the bulk of the material 45 within the packing chamber 151 so that the compression is exerted upon the shaft 153 from all sides.

From the foregoing descriptive matter, it

will be understood that the essential feature of the invention resides in the idea, and 50 development thereof, of feeding packing material into a substantially closed chamber as the material contained therein is worn away by friction.

I claim as my invention:

55 1. In a packing device of the class described, the combination of: a body providing a packing chamber directly surrounding the shaft to be packed; walls providing a receptacle for holding a packing material; and rotatable means comprising a spiral member engaging said packing material and disposed between said packing chamber and said receptacle for forcing said packing material into said packing chamber. 60

2. In a packing device of the class described, the combination of: a body forming a packing chamber; a shaft extending through said chamber; walls forming a receptacle for containing a packing material; 70 and rotatable means therebetween, and comprising a spiral member which engages said packing for manually forcing said packing against said shaft.

75 3. In a packing device of the class described the combination of: a shaft; a body forming a packing chamber around said shaft; walls forming a receptacle around said shaft for holding a supply of packing material; and manually operable means 80 comprising a spiral member engaging packing disposed around said shaft for forcing said packing into said packing chamber.

4. In a packing device of the class described, the combination of: a shaft; a body 85 forming a packing chamber about said shaft; walls forming a receptacle for holding a supply of packing material; and a rotatable screw arranged therebetween for continually forcing said packing material 90 into said chamber without reducing the pressure in said chamber.

In testimony whereof, I have hereunto set my hand at Los Angeles, California, this 4th day of October, 1922.

AUGUST L. SEGELHORST.
